UNITED STATES PATENT OFFICE.

SIMON SHUFFLEBARGER AND WILLIS SHUFFLEBARGER, OF EDDYVILLE,
ILLINOIS.

JOURNAL-BOX.

SPECIFICATION forming part of Letters Patent No. 321,651, dated July 7, 1885.

Application filed March 9, 1885. (No model.)

To all whom it may concern:

Be it known that we, SIMON SHUFFLEBARGER and WILLIS SHUFFLEBARGER, both of Eddyville, in the county of Pope and State of Illinois, have invented a new and Improved 5 Journal-Box, of which the following is a full, clear, and exact description.

This invention relates to certain new and useful improvements in journal-boxes provided with anti-friction rollers; and the object of the invention is to hold the rollers in place more securely, to reduce the wear, and make the box more durable.

The invention consists in details of construction and the arrangement of parts, as will be fully set forth and described hereinafter, and pointed out in the claims.

Reference is to be had to the accompanying drawings, forming part of this specification, in which similar letters of reference indicate corresponding parts in both the figures.

Figure 1 is a cross-sectional view of our improved journal-box on the line *x x*, Fig. 2. Fig. 2 is a longitudinal sectional view of the 25 same on the line *y y*, Fig. 1.

The axle A is provided near its end with an annular groove, B, adapted to receive the anti-friction roller C, and forming a head, D, on the end of the axle. The box is formed of 30 the upper and lower sections or halves, E and F, each provided with a semicircular recess or cavity, G, for receiving the rollers C and the axle. Each section is provided in its outer end with an inwardly-tapered semicircular 35 recess, I, forming an opening in which the head D is located. The anti-friction rollers

C are held in the groove B in the axle by a split steel spring-band, H, passed around them. The two sections E and F are held together by four bolts, J, passed through them to at the corners and having nuts K. An oil-channel, L, leads from an oil chamber or box, M, formed on the top of the upper section, E, and provided with a hinged cover, N, to the cavity containing the rollers C. A vertically-sliding dovetailed plate, P, closes the end opening of the box, and prevents sand and dust from passing into the box. The axle and the rollers C are thoroughly lubricated, as the roller C must pass through the oil in the cavity G in the bottom section, F. The axle A, the rollers C, and the band H are made of steel, and thus last very long and do not wear off.

The box is very simple in construction, and 55 can be taken apart very easily.

Having thus described our invention, what we claim as new, and desire to secure by Letters Patent, is—

In a journal, the combination, with the axle 60 having the annular groove B, of the box-sections E F, provided with cavities G, the anti-friction rollers C in the groove B, and cavities G, and of the split steel spring-band H, surrounding the said rollers, substantially as 65 herein shown and described.

SIMON SHUFFLEBARGER.
WILLIS SHUFFLEBARGER.
